DISPLAY RACK FOR SHOES

Michael Wahl, Searington, Long Island, N.Y., assignor to Wahl Associates, Inc., Long Island City, N.Y.

Filed May 20, 1971, Ser. No. 145,590

Term of patent 14 years

Int. Cl. D6—06

U.S. Cl. D6—116

FIG. 1.

FIG. 2.

FIG. 3.

FIG. 4.

FIG. 5.

FIG. 6.

FIG. 7.

FIG. 1 is an elevational perspective view of a display rack for shoes showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side view thereof; and

FIG. 7 is a right side view thereof.

The broken line representation of a pair of shoes on the display rack in FIG. 1 is for purposes of illustration only.

I claim:

The ornamental design for a display rack for shoes, substantially as shown and described.
